SNOW PLOW

Walter Hewitt, Longmire, Wash., assignor of
one-half to Marlow Glenn, Longmire, Wash.

Application July 28, 1933, Serial No. 682,596

4 Claims. (Cl. 37—43)

This invention relates to snow plows and aims primarily to provide a snow plow especially designed and adapted for completely clearing or removing snow from highways, roads, streets, 5 trails, sidewalks, paths, or the like, when the snow has not been allowed to accumulate to excessive depths thereon.

Broadly contemplated by the present invention is the provision of a novel and improved snow 10 plow and rotor particularly adapted for rapid and ready attachment to an automotive road vehicle in such a manner that the rotor thereof may be driven either by the power plant of said vehicle or by a separate engine drive, and which 15 is also adapted for similar detachment from said vehicle to permit of the latter being used for other purposes.

The invention also contemplates a novel method for clearing snow from a highway, roadway, 20 street, or the like, which consists of accumulating the snow from substantially one-half the width of the same upon the other half thereof to provide on said cleared half a path for snow transporting equipment, and as a separate and successive step clearing the snow from said other half together with the accumulations thereon and depositing same in said snow transporting equipment.

With the above in view, the invention essentially resides and is more particularly concerned 30 in the provision of a novel and improved snow plow, which in its preferred embodiment comprises an angularly disposed plow blade adapted to be detachably mounted upon or connected 35 to an automotive road vehicle for pushing the snow aside as said vehicle advances; a rotor mounted at the snow accumulating end of said plow blade for throwing the pushed snow further aside, said rotor being adapted to be driven either 40 by the power plant of said vehicle or by a separate engine drive as desired and found most expedient; and means controllable from the driver's seat of said vehicle for raising the plow blade and rotor relative to the ground; all of 45 which are important features and elements of the present snow plow and are to be correlated in the broad aim of enhancing the efficiency of the same for the uses and purposes for which it is especially designed and primarily intended.

50 The above, and additional objects which will hereinafter be more specifically treated are attained by such means as are shown in the accompanying drawings, described in the following specification and then more clearly pointed

out in the claims, which are appended hereto and form part of this application.

With reference to the drawings, in which there are illustrated several embodiments of the invention and throughout the several views of which 5 like characters of reference designate similar parts:—

Fig. 1 is a top plan view of a snow plow comprehended by the present invention, as it would appear when operatively connected to its 10 correlated automotive road vehicle.

Fig. 2 is a side elevation thereof.

Fig. 3 is a front elevation of the same.

Fig. 4 is an enlarged fragmentary perspective view illustrating the preferred mode of attaching the present snow plow to its correlated automotive road vehicle.

Fig. 5 is a transverse section taken through 5—5 of Fig. 1, illustrating the manner of mounting the push bars upon castor wheels.

Figs. 6, 6A and 7 are vertical longitudinal sections taken through 6—6, 6A—6A and 7—7, respectively, of Fig. 1, illustrating one of the mechanisms for effecting the mechanical raising and lowering of the plow blade and rotor.

Fig. 8 is a similar section of the plow rotor taken through 8—8 of Fig. 1, certain parts being broken away for clarity of illustration.

Fig. 9 is a top plan view of a slightly modified form of the snow plow, embodying a separate engine drive for the plow rotor and manually operable mechanism for raising and lowering the plow blade and rotor.

Fig. 10 is an enlarged fragmentary view in medial horizontal section of the mechanism for manually raising and lowering the plow blade and rotor of said modified form.

Fig. 11 is a transverse vertical section taken through 11—11 of Fig. 10.

Fig. 12 is a top plan view of another modified 40 form of snow plow, embodying hydraulic apparatus for raising and lowering the plow blade and rotor.

Fig. 13 is a side elevation thereof.

Fig. 14 is a vertical transverse section taken 45 through 14—14 of Fig. 12 illustrating one of the hydraulic cylinders for raising and lowering the plow blade and rotor of this modified form.

Fig. 15 is a fragmentary longitudinal vertical section taken through 15—15 of Fig. 12, illustrating the power take-off for driving the plow rotor and hydraulic pump from the transmission of the vehicle.

Fig. 16 is a fragmentary horizontal section of 55

the hydraulic control valve taken through 16—16, of Fig. 13.

Fig. 17 is a diagram of a typical fleet of units employed in clearing roads or streets, and illustrating the process of clearing same according to my improved method.

Fig. 18 is a vertical transverse section of same taken through 18—18 of Fig. 17.

Fig. 19 is a diagrammatic front elevation of my snow plow, as it would appear when clearing a snow bank from the side of a road or highway.

Fig. 20 is a top plan view of a further modified form of snow plow, of the type employed for clearing side walks, paths, trails, or the like.

Fig. 21 is a side elevation thereof, and

Fig. 22 is a front elevation of the same.

Before taking up a more detailed description of the drawings, a general exposition of the specific purposes, functions and advantages of the snow plow evolved by the present invention will be undertaken.

Heretofore, in clearing or removing snow of any depth up to approximately twelve inches, from highways, roads, or streets, it has been customary to generally employ road vehicles equipped at their forward ends with plain plow blades, adaptable to be raised and lowered from the roadway, which plow blades merely pushed the snow off to one side and banked the same thereat, and after each successive fall of snow, such blade plow would traverse the roadway and add to the bank of snow previously formed, thereby progressively decreasing or narrowing the effective width of the roadway, until such effective width was so decreased that it was impossible for the blade plow to again traverse the roadway or operate thereover. In other words, by merely and/or successively pushing the snow off to the side of the roadway, in the manner above described, the problem of snow removal is not solved, but is materially aggravated.

Wherefore, it is the primary and fundamental object of this invention to provide a snow plow, which will effectively remove snow of any depth up to approximately twelve inches from highways, roads, or streets; which will positively clear and maintain the full width of same for use by vehicular traffic at all times and will not create any snow banks at the sides thereof, by reason of the fact that the snow is discharged or thrown by the present snow plow at or to a distance from the side of the highway or road, or is discharged into dump trucks in clearing streets; which will rapidly traverse a highway, road or street and clear many miles of same in a comparatively short time; and which is also adaptable for clearing paths, trails, sidewalks, or the like.

Beginning now the more detailed description of the invention by reference to the accompanying drawings, and referring here more particularly to Figs. 1 to 8, inclusive, wherein the numeral 25 generally designates the chassis of an automotive vehicle or truck of any well known type, 26 the vehicle engine or power plant, 27 the vehicle transmission, 28 the vehicle driver's seat, and 29 the front axle of the vehicle, to which is detachably secured my novel and improved snow plow herein generally designated by the numeral 30.

To detachably secure the snow plow 30 to the vehicle 25 I provide an angle iron 31 which is mounted upon the forward side and top face of the front axle 29 between the spring mountings 28a thereof, and is rigidly clamped thereto by

U-bolts 32 and plates 33. Riveted or otherwise fixedly secured in spaced relation upon the front or outer forward face of the angle iron 31 are lug plates 34 to which are pivotally connected, as by pins 35, the rear ends of forwardly extending diverging push bars or struts 36, the forward ends of which are rigidly secured in divergent relation by an angularly disposed structural steel framework, substantially rectangular in formation, and herein generally designated by the numeral 37, said forward ends of said push bars 36 and framework 37 being in the present instance supported upon the ground by ball bearing castors or swivelling wheels 38 mounted upon upwardly offset laterally disposed brackets 39 extending outwardly from the forward ends of the push bars 36 and rigidly secured thereto adjacent the juncture of the same with the framework 37.

Fixedly secured to the lower corner portions of the framework 37 are vertically disposed guideways 40, wherein blocks 41 are slidably mounted, to the outer or forward faces of which is rigidly secured, in any well known manner an angularly disposed and vertically adjustable plow blade or mold board 42, which blade is adapted to extend completely across the pathway of the vehicle 25, see Figs. 1 and 3, and is curved outwardly in the direction of its width or height, and upon its upper edge is slightly return bent, as at 42a, whereby any snow which may reach said upper edge is deflected downwardly and is not permitted to fall behind the plow blade 42. Detachably secured, as by bolts 43 to the lower edge of the plow blade or mold board 42 is a replaceable cutter plate or strip 44, which latter when worn is rapidly and readily replaced, thereby materially increasing the life of the plow blade or mold board 42.

Seated within the upper portions of the sliding blocks 41 and fixedly secured therein, as by pins 45, see Fig. 7, are upwardly extending vertically disposed plow blade adjusting screws 46 normally engaged at their upper ends within nuts 47, see Fig. 7, mounted for rotation and against axial movement within sectional casings 48, which are fixedly seated within gusset plates 49 rigidly secured to the upper corners of the framework 37, see Figs. 2 and 3.

The nuts 47 are connected by bevel gearing 50, see Fig. 7, to the forward ends of rearwardly extending and converging articulated shafts 51, which ends are journaled for rotation within rearwardly extending sleeves 48a bolted, or otherwise rigidly secured, to the rear sides of the sectional casings 48, see Figs. 1, 2 and 7, said articulated shafts at their rear or convergent ends being journaled for rotation in spaced parallel relation within a sectional control box 52 mounted upon the upper end of a headstock or hollow post 53 hereinafter more fully described. Also journaled for rotation within the control box 52 and interposed in spaced parallel symmetric relation between the rear ends of the articulated shafts 51 is the rear end of a forwardly extending articulated rotor propelling shaft 54, which latter is interconnected within the control box 52 with the articulated shafts 51 by dual trains of spur gearing 55, see Figs. 6 and 6A, the spur gears of which are freely or loosely mounted upon their respective shafts, said rotor propelling shaft 54 having its spur gears connected by reversing bevel gearing 56 to the upper end of a vertically disposed countershaft 57, which extends downwardly within the headstock 53 in concentric

spaced relation thereto, and at its lower end is driveably connected, in any well known manner, to a power take-off 58 operatively connected to the vehicle transmission 21, said headstock 53 being rigidly secured at its base or lower end upon the casing of said power take-off 58.

Interposed between the spur gears of the articulated shafts 51 and splined upon the latter are axially sliding double clutch members 59 adapted to alternately and selectively engage complementary clutch jaws 66 formed upon the inner faces of said spur gears, see Fig. 6A. The clutch members 59 are moved into and out of engagement with the clutch jaws 66 by forked members 61 fixedly secured at their upper ends to shifting rods 62 mounted for axial movement within the upper portion of the control box 52 in vertically aligned relation with their respective articulated shafts 51, said rods 62 at their rearwardly projecting ends being pivotally connected to control or shifting levers 63 operatively mounted upon the rear side of said control box 52, see Fig. 6A. Also interposed between the opposing gears of the bevel gearing 58 of the rotor propelling shaft 54 and splined upon the latter is an axially sliding double clutch member 64 adapted to alternately and selectively engage complementary clutch jaws 65 formed upon the inner faces of said opposing bevel gears, see Fig. 6. The clutch member 64 is moved into and out of engagement with the clutch jaws 65 by a forked member 66 fixedly secured at its upper end to a shifting rod 67 mounted for axial movement within the upper portion of the control box 52 in vertical alignment with respect to the rotor propelling shaft 54, said rod 67 at its rearwardly projecting end being pivotally connected to a control or shifting lever 68 operatively mounted upon the rear side of said control box 52, see Fig. 6. To restrainingly engage the shifting rods 62 and 67 in a neutral or central position I provide the forward ends of same with peripheral grooves 62a and 67a, respectively, wherein spring-pressed balls 62b and 67b, respectively, are adapted to normally seat, when said shifting rods are in their respective neutral positions, as above described, and as will be manifest and apparent by referring more particularly to Fig. 6A.

Returning now to the forwardly extending rotor propelling shaft 54 for further description of the same, said shaft at its forward end is connected by bevel gearing 69 to the inner end of a laterally disposed articulated and telescopic shaft 70, the adjacent ends of said shafts 54 and 70 being journalled for rotation within a casing 71, which in the present instance encloses the bevel gearing 69 and is preferably rigidly secured to and supported upon the push bars 36, as by a bracket or brace member 12. However, if desired, the casing 71 may be detachably secured to and supported upon any suitable portion of the vehicle chassis 25, as for example, to the bumper frame of the latter.

The telescopic shaft 70 is journalled for rotation at its outer end within a casing 73 fixedly secured to the rear or end wall of a rotor housing 74, which is bolted, or otherwise detachably secured, at its periphery as by bolts 75, to the following or rear end of the angularly disposed plow blade or mold board 42, see Fig. 1, and which in the present instance is completely open at its forward end for the purpose of permitting free and unimpeded entrance of the snow thereto, as will hereinafter be made more apparent. The aforesaid outer end of the telescopic shaft 70

is connected, within the casing 73, by bevel gearing 76 to the rear terminal of a rotor shaft 77, the rear end portion of which is journalled for rotation within the rear or end wall of the rotor housing 74, while upon the forward end portion of said rotor shaft 77, which extends or projects into said rotor housing 74, a rotor generally designated by the numeral 78 is operatively mounted in any well known or conventional manner, to rotate within the housing 74, all as more clearly shown in Fig. 8, said rotor, as now constructed, comprising a hub member 78a provided with radially disposed wings 78b having their outer terminal portions slightly offset, upon which portions are fixedly secured arcuate blades 78c. Formed within the peripheral walls of the rotor housing 74, preferably upon the outer side of the latter, see Figs. 1 and 3, is a delivery or discharge chute 79, which may be formed integrally therewith, or otherwise rigidly secured thereto.

Obviously, the type of snow plow hereinbefore described contemplates the mechanically raising and lowering of the plow blade or mold board 42, with respect to the ground, by the power plant or engine 26 of the vehicle 25, also the driving 25 of the rotor 78 by such plant or engine, thus providing a snow plow which is comparatively light and compact in construction, and one that may be rapidly and readily handled while in use and also while being attached to or detached from the vehicle 25.

Further while I have herein shown and described the plow blade or mold board 42 and rotor 78, as detachably secured to the front axle of the vehicle 25, I desire to have it understood that such plow blade and rotor may be attached to any other suitable part of the vehicle, as desired and found expedient, the present showing being merely by way of illustration.

The snow plow 30, as herein shown and described, is adapted to be rapidly and readily attached, as hereinbefore stated, to any standard make of automobile truck and similarly detached therefrom, so that said truck may be utilized or employed for general hauling or trucking purposes, hence, when it is desired to use the snow plow 30 to clear a highway, road, street, or the like, the truck 25 is driven up to the snow plow and the rear ends of the push bars 36 are attached or clamped to the front axle 29 by the angle iron 31, U-bolts 32 and plates 33 in a few minutes, following which the headstock 53 is installed and its countershaft 57 connected to the vehicle power take-off 58, and the casing 71 of the rotor propelling shaft 54, if not secured to the push bars 36, is attached to the bumper frame of the vehicle, whereupon the snow plow 30 is ready for snow clearing operations. In order to facilitate installation of the headstock 53 the articulated shafts 51 and 54 may be disconnected or uncoupled, at points adjacent the control box 52, and after installation of the headstock is completed such shafts are again connected or coupled, in an obvious manner.

In a snow clearing operation by the snow plow 30, the vehicle operator starts the vehicle engine 26 and manipulates the controls, not shown, of the power take-off 58, to thereby impart rotation to the countershaft 57, bevel gearing 58, and the dual or reversing trains of spur gearing 55, whereupon the operator manipulates the control levers 63 to mechanically raise or lower the plow blade or mold board 42 to the desired elevation relative to the ground, this being accomplished through the media of the double clutch members 59, articu-

lated shafts 51, bevel gearing 50, nuts 47, screws 46 and blocks 41. If the plow blade 42 is to be raised the operator pulls the control levers 63 backwardly, and if said plow blade is to be lowered the operator pushes said control levers forwardly, and in either event, the clutch jaws 60 of the train of spur gearing 55 involved are engaged by the complementary jaws of the clutch members 59, which latter in turn impart rotation to the articulated shafts 51, bevel gearing 50 and nuts 47, the rotating of which causes upward or downward movement of the screws 46, sliding blocks 41 and plow blade 42, dependent of course upon the direction of rotation of the nuts 47, as will be obvious and manifest. Having effected and obtained the desired adjustment of the plow blade 42, the operator then pushes the rotor control lever 68 forwardly to engage the clutch member 64 with the complementary jaws 65 of the forwardly disposed bevel gear of the bevel gearing 56, whereby rotation is imparted to the rotor propelling shaft 54, bevel gearing 59, telescopic shaft 70, bevel gearing 76, rotor shaft 77 and rotor 78. The operator then starts the vehicle 25 forwardly into the snow to be cleared, by manipulating the usual vehicle controls, not shown, and as the vehicle advances into the snow the angularly disposed plow blade 42 pushes the snow aside, or in other words the snow is caused to travel along the face of the blade 42, and as it is thus pushed aside such snow is caused to enter the open front end of the rotor housing 74 wherefrom it is discharged or thrown by the rotor 78 in an obvious manner through the delivery chute 79, said snow in most instances being thrown or discharged substantially in a lateral direction to a distance of fifty to one hundred feet from the path being cleared.

Actual experience and exhaustive tests of the present snow plow have shown and demonstrated that the same will clear snow from many miles of highways, roads, streets, or the like, in both directions, in a comparatively short time, providing, however, that the snow does not exceed approximately twelve (12") inches in depth.

When the truck 25 and its correlated plow 30 are to be moved from place to place, the plow blade 42 and rotor 78 are elevated substantially to the limit of their upward adjustment, so that such plow blade and rotor will be substantially clear of the ground and will not drag thereon or contact any unevenness therein while in transit. In this connection, it is to be here noted that all manipulations or adjustments of the plow 30 and rotor 78 are effected from the vehicle driver's seat 28, and that it is unnecessary for the operator to leave the same to effect any manipulation or adjustment of said plow.

When it is desired to detach or disconnect the snow plow 30 from the truck 25, such detachment or disconnecting may be accomplished in a comparatively short time, by merely detaching or disconnecting the clamped angle iron 31 from the front axle 29 of the vehicle, removing the headstock 53 from the casing of the power take-off 58, and when necessary detaching the brace 72 of the bevel gear casing 71 from the bumper frame of the vehicle, whereupon the truck 25 is ready and in condition for ordinary commercial or hauling purposes.

In the slightly modified form of snow plow illustrated in Figs. 9 to 11, inclusive, which form contemplates a separate engine drive for the plow rotor thereof and manually operable mechanism for raising and lowering the plow blade of same, the numeral 80 in said figures generally designates

an automobile truck of any well known type, 81 the driver's seat thereof, and 82 the front axle of the same, to which is detachably secured the slightly modified form of snow plow herein generally designated by the numeral 83.

The snow plow 83 is detachably secured to the front axle 82 of the vehicle 80 in the identical manner to that hereinbefore described for the snow plow 30, and with this end in view the numeral 84 designates lug plates, corresponding to 10 the lug plates 34 of the plow 30, to which are pivotally connected, as by pins 85, the rear ends of forwardly extending and diverging push bars or struts 86, which are rigidly interconnected at their forward ends by an angularly disposed 15 structural steel framework 87, said forward ends of said push bars and said framework being normally supported upon the ground by castors or swivelling wheels 88 depending from brackets 89 rigidly secured to and extending laterally from 20 the forward ends of the push bars.

Fixedly secured to and extending laterally from the sides of the framework 87 are vertically disposed guideways 90, wherein blocks 91 are slidably mounted, to which is rigidly secured an angularly disposed vertically adjustable plow blade or mold board 92, substantially identical in construction to the plow blade 42. Fixedly secured within the blocks 91 are upwardly extending vertically disposed plow blade adjusting screws 93, 30 which at their upper ends extend through sectional casings 94 fixedly seated within brackets 95 rigidly secured to the framework 87, said sectional casings 94 being of the same type as the sectional casings 48 hereinbefore described. 35

Operatively connected to the screws 93, within the sectional casings 94, in the identical manner the forward end of the articulated shafts 51 are connected to the screws 46, are the forward ends of rearwardly extending and converging articulated plow adjusting shafts or rods 96, which ends are journalled for rotation within sleeves 94a extending rearwardly from said sectional housings 94, see Fig. 9, said articulated shafts at their rear or convergent ends being journalled 45 for rotation in spaced parallel relation within a sectional control box 97, operatively mounted in any desired manner upon any suitable portion of the vehicle 80, within convenient reach of the driver's seat 81 thereof, as for example, upon the vehicle dash board, not shown. Mounted for rotation and axial movement within the control box 97 and interposed in spaced parallel symmetric relation between the rear ends of the articulated shafts 96 is a manually operable stub 55 shaft 98 provided upon its rearwardly projecting end with a handwheel 99, see Figs. 9 and 10, said stub shaft being provided within the control box 97 with a spur gear 100 which is keyed, or otherwise rigidly secured thereon, adapted to jointly 60 mesh with spur gears 101 keyed, or otherwise fixedly secured, to the enclosed rear ends of the articulated shafts 96 in offset relation with respect to each other, see Fig. 10, said spur gear 100 being also adapted, when its correlated stub 65 shaft 98 is axially moved within the control box 97, to selectively and individually mesh with either one of the spur gears 101, depending of course upon the direction of axial movement of said shaft, as will be manifest and apparent. To 70 restrainingly maintain the spur gear 100 in joint mesh with the spur gears 101 and the stub shaft 98 in a corresponding intermediate position I provide the latter adjacent its forward end with a peripheral groove 98a wherein a spring- 75

pressed ball 88b, mounted within a sleeve extension 91a of the box 91, is adapted to seat when said stub shaft 88 is in its intermediate position aforesaid, and as substantially illustrated in Fig. 10.

Transversely disposed and rigidly supported upon the push bars 88, between the vehicle 80 and the snow plow 83, is an internal combustion engine, or other suitable power unit, 102, wherefrom an articulated driving shaft 103 extends in substantially laterally disposed relation to the snow plow 83, said shaft being adapted to drive a rotor unit herein generally designated by the numeral 104, which unit is identical in construction to the rotor unit hereinbefore described for the snow plow 30, and in this connection, it should be noted that the rotor unit 104 is also detachably connected, as by bolts 105, to the rear or following end of the plow blade 92, as shown more clearly in Fig. 9. The engine or power unit 102 is adapted to be controlled and regulated from the driver's seat 81, by any well known means, not shown.

The snow plow 83 is adapted to be rapidly and readily attached to its correlated automobile truck and similarly detached therefrom, substantially in the same manner as the snow plow 30 is attached to and detached from its correlated truck 25, that is to say, the push bars 88 are secured to the front axle 82 of the truck exactly as hereinbefore described for the push bars 38, following which the sectional control box 91, is installed upon the truck in the position selected therefor, whereupon the truck and snow plow are ready for snow clearing operations.

In a snow clearing operation by the snow plow 83, the vehicle operator first adjusts the plow blade 92 relative to the ground by axially moving the handwheel 99 to its mid-position, at which time the spur gear 100 is in joint mesh with the spur gears 101, following which the operator turns the handwheel right or left to raise or lower the plow blade 92 in an obvious manner. If for any reason it is necessary to raise or lower either end of the plow with respect to the other end, the vehicle operator pulls or pushes upon the handwheel 99 to cause the spur gear 100 to individually mesh with one or the other of the spur gears 101, depending upon which end of the plow blade 92 is to be raised or lowered, so that when the handwheel 99 is rotated in either direction raising or lowering of the particular end of the plow blade 92 is effected. Having secured the desired adjustment for the plow blade 92 the vehicle operator then starts the engine or power unit 102 from the driver's seat 81, by any suitable means not shown, to thereby actuate the rotor unit 104, following which the operator starts the engine or propelling plant of the vehicle 80 and manipulates the usual vehicle controls, not shown, to start the vehicle 80 and snow plow 83 forwardly, and as the latter advances into the snow the plow blade 92 pushes the snow aside and the rotor unit 104 throws such snow further aside, all in the manner hereinbefore described for the snow plow 30. Upon completion of snow clearing operations the snow plow 83 is detached from the truck 80 and the latter is then ready for ordinary commercial or hauling purposes.

In the further slightly modified form of snow plow illustrated in Figs. 12 to 16, inclusive, which form contemplates utilizing the propelling or power plant of the vehicle for driving the plow 75 rotor thereof and hydraulic apparatus for rais-

ing and lowering the plow blade of same, the numeral 106 in said figures generally designates an automotive truck of any well known type, 107 the vehicle engine or power plant, 108 the vehicle transmission, 109 the vehicle driver's seat and 110 5 the front axle of the vehicle, to which is detachably secured the further slightly modified form of snow plow herein generally designated by the numeral 111.

The snow plow 111 is detachably secured to the 10 front axle 110 of the vehicle 106 in the identical manner hereinbefore described for the snow plow 30, hence, the numeral 112 designates lug plates, corresponding to the lug plates 34 of the plow 30, to which are pivotally connected, as by pins 113, 15 the rear ends of forwardly extending and diverging push bars or struts 114, to which is rigidly interconnected at their forward divergent ends an angularly disposed plow blade or mold board 115, which latter, per se, and with the exception 20 that it is directly and rigidly connected to the struts 114, is substantially identical in form and construction to the plow blade 42 hereinbefore described. In order to strengthen and properly brace the forward end portions of the push bars 25 114 I provide a tie bar or spacer 116, which latter is interposed between said forward end portions and is rigidly secured thereto at its terminals, in any well known manner.

Fixedly secured to the push bars 114 adjacent 30 their forward ends are upwardly extending vertically disposed brackets 117, the upper ends of which are bent outwardly at right angles and terminate in heads 117a, to which are fixedly secured the upper ends of depending vertically disposed pistons 118 having their major portions axially and slidably disposed within hydraulic cylinders 119, which latter are normally supported upon the ground by castors or swivelling wheels 120 operatively attached to their lower ends as by bolts 120a 40 substantially in the manner more clearly illustrated in Fig. 14. To effectively and properly guide the brackets 117 for sliding movement relative to the hydraulic cylinders 119 during axial movement of the pistons 118 within the latter, I 45 provide the peripheral walls of said cylinders with integral bifurcated lugs 119a adapted to normally straddle the vertical reinforcing web portions 117b of the brackets 117, as shown more clearly in Fig. 12.

Connected to the lower ends of the hydraulic cylinders 119 are the forward ends of rearwardly extending fluid pressure supply and exhaust pipes 121 having flexible valved couplings 121a interposed therein, for a purpose which will herein-after be made more apparent, said supply and exhaust pipes at their rear ends being connected to adjacent or contiguous branches of a four-way valve 122 having a plug 123 provided with a diametrically disposed port 123a adapted to normally or continuously register at its forward end with an arcuate channel or groove 122a formed within the body of said four-way valve 122, see Fig. 16, and with which the rear ends of said supply and exhaust pipes 121 are in normal and continuous communication. To operate the four-way valve 122 I provide a manually operable actuating lever 124, which is fixedly secured to the plug 123, in any well known manner. Connected to the other or opposing branches of the four-way valve 122, for alternate and selective registration with the rear or opposite end of the port 123a, are a fluid pressure supply pipe 125 and a fluid pressure exhaust pipe 126, respectively, said fluid pressure supply pipe 125 being connected at 70 75

its opposite end to the delivery or discharge side of a pump 127, while the opposite end of said fluid pressure exhaust pipe 126 is connected to the inlet or suction side of said pump 127, which latter is 5 preferably driven by an articulated shaft 128 from a power take-off herein generally designated by the numeral 129. As shown in Fig. 15, this power take-off is provided with a casing 129a, wherein the forward end of the pump driving shaft 128 10 is journalled and extends, and similarly journalled and extending within the opposite end of said casing is the rear end of a forwardly extending sectional rotor propelling shaft 130, the adjacent or inner ends of said shafts being adapted to abut at 15 a point within the casing 129a, substantially midway its length. Splined, or otherwise mounted, for axial movement upon the enclosed ends of the shafts 128 and 130 are jaw clutch members 128a and 130a, respectively, and freely or loosely 20 mounted upon the abutting terminals of the shafts 128 and 130 is a gear 131, which is normally in continuous mesh with a live gear 108a of the vehicle transmission 108, said gear 131 having complementary jaw clutch members 131a and 131b 25 formed upon its ends adapted to be engaged respectively by the jaw clutch members 128a and 130a, whereby the shafts 128 and 130 may be independently or separately driven from the gear 131 or such shafts may be simultaneously driven 30 from the same therefrom, as desired or found expedient. To rapidly and readily effect engagement of the jaw clutch member 128a with its complementary jaw clutch member 131a, and disengagement of the same therefrom, I provide a shipper or manually 35 operable clutch lever 128b therefor, and to similarly effect engagement of the jaw clutch member 130a with its complementary jaw clutch member 131b, and disengagement of the same therefrom, I provide a shipper or manually operable clutch 40 lever 130b therefor, both of said levers 128b and 130b being disposed within easy reach of the vehicle operator's driving position, as will be obvious by referring more particularly to Figs. 12 and 13.

Returning again to the forwardly extending 45 sectional rotor propelling shaft 130, for further description of the same, said shaft is provided with a flexible coupling 130a at a point intermediate the length thereof, for a purpose which will hereinafter be made more apparent, and at 50 its forward end such sectional shaft is connected by bevel gearing 132 to the inner end of a laterally disposed articulated telescopic shaft 133, the adjacent ends of said shafts being journalled for rotation within a casing 134, which encloses the 55 bevel gearing 132 and may be either rigidly secured to the push bars 114, as by a bracket 135, or it may be detachably secured to and supported upon any suitable portion of the vehicle 106, substantially in the manner hereinbefore described 60 for the casing 71 of the snow plow 30.

The laterally disposed telescopic shaft 133 at its outer end is adapted to drive a rotor unit herein generally designated by the numeral 136, which unit is identical in construction to the 65 rotor unit hereinbefore described for the snow plow 30, and is also detachably secured or connected, as by bolts 137, to the rear or following end of the plow blade 115, as shown more clearly in Fig. 12.

70 The snow plow 111 is adapted to be rapidly and readily attached to its correlated automobile truck 106 and similarly detached therefrom, substantially in the same manner, as the snow plow 30 is attached and detached from its correlated truck 75 25, that is to say, the push bars 114, are secured

to the front axle 118 of the truck exactly as hereinbefore described for the push bars 36, following which the detachable forward section of the rotor propelling shaft 130 is coupled to the rear section thereof by the flexible coupling 130a, 5 it being here understood that such rear section of the rotor propelling shaft 130 normally or permanently remains in the vehicle 106, following which the forward sections of the fluid supply and exhaust pipes 121 are coupled to the 10 rear sections of same by the flexible valved couplings 121a, which latter also normally or permanently remain in the vehicle 106, said valved couplings having automatic valves of any well known type, not shown, adapted to automatically 15 close when the sections of the pipes 121 are disconnected, to thereby positively prevent escape of fluid from the sections of the pipes 121. Upon completion of the foregoing the truck and its correlated snow plow are in readiness for snow 20 clearing operations.

In a snow clearing operation by the snow plow 111, the vehicle operator, if desired and necessary, first adjusts the plow blade 115 relative to the ground, by starting the vehicle engine 107 25 to drive the live gear 108a and gear 131, then manipulates the shipper lever 128b to effect engagement of the jaw clutch member 128a with its complementary jaw clutch member 131a of the gear 131 and thus drive the shaft 128 and its 30 pump 127 to build up the desired and necessary hydraulic or fluid pressure therein, following which the operator manipulates the lever 124 of the valve 122 to bring the port 123a into registration with the fluid supply pipe 125, whereupon 35 the fluid pressure passes through said port into the channel 122a, and from thence through the pipes 121 to the hydraulic cylinders 119, wherein such fluid pressure exerts upward axial pressure upon and effects elevation of the pistons 118, 40 which latter in turn, through the media of their brackets 117, elevate the forward ends of the push bars 114 and simultaneously therewith raises their correlated rigidly interconnected plow blade 115 from the ground, it being here noted and observed in this type of construction, that all vertical adjustment of the forward ends of the push bars 114 and their correlated and rigidly interconnected plow blade 115 is effected about the pivot pins 113 of said push bars 114, while in 45 the previously described constructions, their push bars normally remained in the same relation to the ground at all times and only their plow blades were vertically adjustable relative to the ground. When the desired elevation has been secured for 50 the plow blade 115 the operator moves the handle 124 of the valve 122 to its closed position, to hold the fluid in the hydraulic cylinders 119, and then manipulates the lever 128b to disconnect or disengage the jaw clutch member 128a 55 from its complementary jaw clutch member 131a, following which the operator manipulates the shipper lever 130b to effect engagement of the jaw clutch member 130a with its complementary jaw clutch member 131b of the gear 131, to thus 60 drive the rotor unit 136 through the media of the propelling shaft 130, bevel gearing 132 and telescopic shaft 133, as will be obvious and apparent, following which the operator manipulates the usual vehicle controls, not shown, to start 65 the vehicle 106 and snow plow 111 forwardly, and as the latter advances into the snow the plow blade 115 pushes the snow aside and the rotor unit 136 pushes the snow further aside, all in the manner hereinbefore described for the snow plows 70 75 75

38 and 83. When it is desired to lower the plow blade 115 for any reason the operator manipulates the lever 124 of the valve 122 to bring the port 123a into communication with the fluid exhaust pipe 128, whereupon the fluid in the hydraulic cylinders 119 is released and is exhausted back to the suction or intake side of the pump 127 in a well known and obvious manner, following which the lever or handle 124 is moved 10 to its closed position. In the present disclosure I have elected for simplicity of illustration and description, to show and describe a valve, as 122, which jointly effects raising and lowering of the pistons 118 and their appurtenant parts, but not 15 independent or separate raising and lowering of such pistons with respect to each other, however, I desire to have it here understood that the present invention also contemplates the provision and use of a valve, which will effect joint or independent raising and lowering of the pistons 118, so that either end of the plow blade 115 may 20 be raised and lowered with respect to the other end, substantially in the same manner as hereinbefore described for the plow blades 42 and 82, the present showing of the valve 122 being merely 25 by way of illustration. Upon completion of snow clearing operations the snow plow 111 is detached in an obvious manner from the truck 106 and the latter is then ready for ordinary commercial 30 or hauling purposes.

By pivotally connecting the plow 111 to the vehicle 106, as at 113, and by providing flexible couplings 121a for the fluid supply and exhaust pipes 121 and also providing a flexible coupling 35 130a for the rotor propelling shaft 130, great flexibility between said vehicle and plow is definitely assured and any unevenness in the surface of the highway, road or street being traversed is effectively and properly compensated for, as 40 will be manifest and evident from the foregoing description and by referring to the accompanying drawings.

As hereinbefore set forth, the present invention also contemplates a novel method for clearing 45 snow from a highway, road, street, or the like, involving transportation of the cleared snow to a dumping point more or less remote from its point of fall, which method is employed when circumstances and conditions positively preclude 50 discharging or throwing the cleared snow off to the side of the highway, etc., etc., in the manner herein described for the snow plows 30, 83 and 111. Accordingly I provide and employ a fleet 55 of units such as diagrammatically illustrated in Figs. 17 and 18, to carry out such novel method, in which figures the numeral 138 generally designates the highway, or other surface being cleared, 139 a conventional type of snow plow unit equipped with an ordinary plow blade, 140 my 60 novel and improved rotary snow plow unit, and 141 a conventional automobile dump truck, which functions as the snow transporting unit.

Briefly stated, the present novel method essentially consists in and is carried out by accumulating or pushing the snow from substantially one-half the width of the highway upon the other half thereof with the conventional type of snow plow unit 139, substantially as shown at 142 in Figs. 17 and 18, to thereby create and 70 provide on such cleared half a path for the dump truck or snow transporting unit 141, as will be manifest and apparent by referring to Fig. 17, then as a separate and successive step traversing the highway with my novel and improved rotary 75 snow plow unit 140 and the dump truck 141,

with the latter slightly in advance of the former, as shown in Fig. 17, for a reason and purpose which will now be made more apparent. As the rotary plow unit 140 advances along the un-cleared half of the highway its plow blade 140a 5 pushes the snow thereon, together with the accumulations 142 deposited on same by the unit 138, towards and into its rotor 140b, which latter in turn discharges or throws the snow into the body of the truck or transporting unit 141, substantially in the manner illustrated more clearly in Fig. 18, it being here noted in this connection that the usual delivery chute 140c is provided with a detachable extension 140d for deflecting the snow downwardly into the body of the truck 141. Manifestly, therefore, by employing the above described method and fleet of units, the entire width of a highway, road, street, or the like, may be cleared of snow in a single traversal thereof by such fleet, thus materially reducing 20 the time the same is closed to vehicular traffic. Furthermore, clearing off highways, etc., etc., with the present novel equipment or units can be efficiently effected at speeds as high as forty miles per hour (40 M. P. H.), so that it is possible, when 25 clearing snow by the above described novel method, for vehicular traffic to follow immediately behind the snow clearing units.

In Fig. 19 I have diagrammatically illustrated 30 my rotary snow plow unit as it would appear when clearing or cutting down a snow bank from the side of a road, or highway, the numeral 143 there-in generally designating an automobile truck, 144 my novel and improved rotary snow plow, 145 the rotor of the latter, and 146 a snow bank at the 35 side of a highway or road 147.

In the operation of clearing or cutting down the snow bank 146, the rotary snow plow 144 is elevated to the desired height, as shown in Fig. 19, then rotation is imparted to the rotor 145 40 and the vehicle 143 is started and steered in such a manner as to cause the rotor 145 to cut into the snow bank, a distance substantially equivalent to one-half of its diameter, see Fig. 19, and inasmuch as the rotor 145 is rotating at 45 a comparatively high speed, said rotor rapidly cuts away the snow in its path and discharges or throws the same a considerable distance from the highway 147. The above described operation may be successively repeated until the entire snow bank 146 is removed or cleared from 50 the side of the highway 147.

In the still further slightly modified form of 55 snow plow illustrated in Figs. 20 to 22, inclusive, which form is particularly adapted and especially suited for clearing side walks, paths, trails, or the like, the numeral 148 generally designates a conventional type of caterpillar tractor of the form and size customarily employed in hand cultivators, which tractor is ordinarily powered 60 by a small internal combustion engine, as 149, which latter is connected through suitable differential gearing 150 with the endless caterpillar belts 151 of said tractor in a well known and obvious manner.

Pivoted connected, as at 152, to the frame of 65 the tractor 148 and extending rearwardly from their pivotal mountings in spaced parallel relation to each other are upwardly offset control or steering handles 153, and integrally formed 70 upon or connected to said handles at their front or pivoted ends are forwardly extending push bars or struts 154, the front end portions of which are laterally and downwardly offset, substantially in the manner illustrated more clearly 75

in Figs. 20 and 21, for a purpose which will now be described. Interconnecting and rigidly secured to the front terminals of the push bars 154 is a plow blade or mold board 155, the upper edge of which is curved forwardly and downwardly, as at 155a, while, the lower edge thereof is provided with a detachable or replaceable cutter plate or strip 155b.

The numeral 148a designates the forward projecting end of the crank or other shaft of the engine 149, to the forward end of which is connected, as by a coupling 156, the rear end of a forwardly extending rotor propelling shaft 157 connected at its front end, as by bevel gearing 158, to a laterally disposed articulated shaft 159, the adjacent ends of said shafts being journaled for rotation within a casing 160, which encloses the bevel gearing 158 and is rigidly connected to or supported from the push bars 154 by a depending bracket or brace 161, see Figs. 20 and 21.

The laterally disposed articulated shaft 159, at its outer end, is adapted to drive a rotor unit herein generally designated by the numeral 162, which unit is of the same general type, as the 25 rotor units hereinbefore described for the rotary snow plows 38, 83 and 111, said rotor unit 162 being in the present instance detachably secured or connected, as by bolts 163, to the rear or following end of the plow blade 155, as shown 30 more clearly in Fig. 20.

In a snow clearing operation with the caterpillar type of rotary snow plow above described, the operator starts the engine 149 and manipulates the usual tractor controls, not shown, to 35 drive or move the tractor plow to the point of snow clearing operation with the plow blade 155 and rotor unit 162 elevated from the ground, so that the same will not contact with any obstructions while the tractor plow is in transit, 40 said rotor unit 162 being disconnected from the engine 149 at such time, by any well known means, such as a clutch, not shown. Upon reaching the point of snow clearing operation the plow blade 155 and rotor unit 162 are lowered 45 and the latter is connected in an obvious manner to the engine 149 to thus effect rotation of the same, whereupon the tractor plow is advanced into the snow on the sidewalk, trail, path, or the like, and as the same advances the plow blade 50 155 pushes the snow to be cleared towards the rotor unit 162, which in turn throws or discharges such snow a considerable distance therefrom, substantially in the manner shown in Fig. 22. As will be obvious and apparent by referring 55 to Figs. 20 to 22, inclusive, vertical adjustment of the plow blade 155 and rotor unit 162 is manually effected by the operator merely raising and lowering the control or steering handles 153.

In the foregoing description and in the accompanying drawings I have shown and described the rotor units as being detachably secured to their correlated plow blades, but, I desire to have it understood, that such rotor units need not necessarily be so connected to the plow blades, but, may be attached to or located upon their propelling vehicles at various points thereon more or less remote from the plow blades thereof, and function thereat with equal efficiency. Further, while I have shown and described the plow blades and rotor units disposed forwardly of their propelling vehicles, it is to be understood that the same may be mounted beneath or behind such vehicles, the present showings and descriptions being merely by way 75 of illustration. Furthermore, by providing de-

tachable rotor units, as herein disclosed, such units, in the event their correlated plows or propelling vehicles become disabled for any reason, may be rapidly and readily detached therefrom and attached to the conventional or ordinary 5 type of blade plows, thus instantly converting same into rotary snow plows.

Manifestly, therefore, the rotary snow plow of the present invention; is extremely simple, durable, and economical in construction; is reliable 10 and efficient in operation; will not readily get out of order; may be rapidly and readily attached to any of the well known types of automobile trucks in general use and similarly detached therefrom to permit such trucks being used for ordinary 15 hauling or trucking purposes during seasons when there is no snow; is mounted and adapted for vertical adjustment either manually, mechanically or hydraulically; is provided with a rotor unit which may be driven by the power plant of 20 its correlated vehicle or by a separate engine drive; will not leave any ridges or windrows on any part of the surface being cleared, thus eliminating all the trouble and annoyance heretofore experienced by reason of the same; and which is 25 adapted to clear snow from highways, etc., up to speeds of forty miles per hour (40 M. P. H.), so that vehicular traffic may follow immediately behind the same.

While I have herein shown and described the 30 invention with sufficient detail to enable those skilled in the art to which it pertains to understand the mode of construction and the principles involved, it is to be understood that there is no 35 intentional limitation herein to the specific form and precise details of construction shown and described, except as expressly defined by the appended claims, and that various modifications of the same may be resorted to without departing from the spirit of the invention or the benefits 40 derivable therefrom. It is also to be understood that certain features of the invention herein disclosed may be employed in and with other combinations than those shown and described.

Having thus fully described my invention, what 45 I claim as new and desire to secure by Letters Patent is:—

1. The combination with a vehicle, of a snow plow comprising a frame pivotally mounted at its rear end upon said vehicle, a wheel mounted upon the forward end of said frame for supporting the same thereat, a plow blade angularly mounted upon the forward end of said frame, a rotor housing similarly mounted upon said forward end adjacent the discharge end of said plow blade with 50 its axis substantially in parallel relation to the longitudinal axis of the vehicle, a rotor in said housing, means for driving said rotor, and means for effecting raising and lowering of the forward end of said frame relative to said supporting 55 wheel.

2. The combination with a vehicle, of a snow plow comprising a forwardly divergent frame pivotally mounted at its rear end upon the forward end of said vehicle, a plurality of wheels mounted in spaced relation upon the forward end of said frame for supporting the same thereat, a plow blade angularly mounted upon the forward end of said frame, a rotor housing mounted upon said plow blade at the discharge end thereof having its lower rim portion disposed in tangential relation to the lower edge of said plow blade and with its axis substantially in parallel relation to the longitudinal axis of the vehicle, a rotor 70 mounted within said housing, means for driving 75

said rotor, and means for effecting raising and lowering of the forward end of said frame relative to said supporting wheels.

3. The combination with an automotive vehicle having a driver's seat, of a detachable snow plow comprising a frame adapted to be removably secured to the forward end of said vehicle, a plow blade angularly mounted upon the forward end of said frame, a rotor casing mounted upon the discharge end of said plow blade having its axis disposed substantially parallel to the longitudinal axis of the vehicle and its lower rim portion disposed substantially in the plane of the lower edge of said plow blade, a rotor mounted within said housing, power means for driving said rotor controllable from the driver's seat, and means also controllable from the driver's seat for regulating the height of the plow blade and rotor casing in relation to the ground.

4. The combination with an automotive vehicle having a driver's seat, of a detachable snow plow comprising a frame adapted to be removably secured to said vehicle, a plow blade angularly mounted upon said frame, a rotor casing mounted upon the discharge end of said plow blade having its axis disposed substantially parallel to the longitudinal axis of the vehicle and its lower rim portion disposed substantially in the plane of the lower edge of said plow blade, a rotor mounted within said housing, power means for driving said rotor controllable from the driver's seat, and means also controllable from the driver's seat for regulating the height of the plow blade and rotor in relation to the ground. 15

WALTER HEWITT.
